UNITED STATES PATENT OFFICE.

WILLIAM T. SMITH, OF PHILADELPHIA, PENNSYLVANIA.

DESIGN FOR A WOVEN FABRIC.

No. 38,933.

Specification for Design.

Patented Dec. 3, 1907.

Application filed September 20, 1907. Serial No. 393,867. Term of patent 7 years.

To all whom it may concern:

Be it known that I, WILLIAM T. SMITH, a citizen of the United States, residing in Philadelphia, Pennsylvania, have invented a new, original, and ornamental Design for Woven Fabric, of which the following is a specification.

The figure in the accompanying drawing is a face view of a piece of woven fabric showing my new design.

I claim:

The ornamental design for woven fabric, as shown.

WILLIAM T. SMITH.
